H. E. VAN NESS

METHOD OF DYEING TEXTILES

Filed Oct. 7, 1922

UNITED STATES PATENT OFFICE.

HENRY E. VAN NESS, OF ELMIRA, NEW YORK.

METHOD OF DYEING TEXTILES.

Application filed October 7, 1922. Serial No. 592,964.

To all whom it may concern:

Be it known that I, HENRY E. VAN NESS, a citizen of the United States, residing at Elmira, in the county of Chemung and State of New York, have invented certain new and useful Methods of Dyeing Textiles, fully described and represented in the following specification and the accompanying drawings, forming a part of the same.

10 This invention relates to a method of dyeing textiles. The invention aims to provide for rapid and economical coloring of predetermined parts of textiles, including both textile materials, such as cotton and 15 other yarns and all kinds of thread, and textile fabrics, whether knitted or woven.

The invention is based on the discovery that it is possible to impregnate a portion of a mass of textile material in such manner 20 that the cross-sectional area of the portion of the material impregnated is either uniform or varies in a predetermined manner throughout the depth of the mass between opposite surfaces thereof. It is believed that 25 the possibility of this has not heretofore been recognized. At all events, it has heretofore been customary, in coloring certain designated parts either of textile materials, or of textile fabrics, to apply the coloring 30 matter separately to each portion of the textile to be colored.

In accordance with the present invention the textile to be dyed is formed into a mass in a regular manner as distinguished from 35 a haphazard manner. Limited quantities of liquid dye are then injected into the mass at designated points thereof. The dye is forced in under such pressure that it penetrates the mass before any substantial part of it is drawn 40 into the pores of the textile by capillary attraction. As a result, the dye injected at each point spreads into the portion of the mass surrounding the line along which it was injected. When, therefore, the textile 45 is extended, it will be found that the textile has been intermittently colored throughout its length in accordance with a predetermined design.

A further feature of the invention consists in insuring the rapid penetration of 50 the dye into the mass by forming narrow openings into the mass and injecting the dye into the mass through such openings.

The invention may be used for a great 55 variety of different purposes, some of which

are herein enumerated in order that the advantages of the invention may be understood.

The invention may be used in "spotting" textile materials, such as yarn or thread. 60 To produce fabric having a mixed or speckled appearance, it has been customary to "spot" the yarn from which the fabric is knitted or woven, or, in other words, to color portions of the yarn located at more 65 or less regular distances along the yarn. This has been accomplished by applying the dye separately to each portion of the yarn to be colored. Thus, each "spot" has been dyed separately, usually while the yarn is 70 traveling. This method of spotting yarn has proved to be slow and expensive and, in practice, necessitates giving each spot the same color and tint.

When the method of the present invention 75 is applied to spotting yarn, a cop of the yarn is formed by winding the yarn upon a bobbin or other core in the usual manner. Limited quantities of dye are then injected into the cop from designated points at one 80 surface thereof, under such pressure that the dye immediately penetrates to the opposite surface. The dye then permeates into the portions of the mass surrounding the line along which it was injected. The portions 85 of the cop which are thus colored extend from the outer surface of the cop to the inner surface thereof. When the cop of yarn is unwound, it will be found that portions of the yarn at regular, but not exactly 90 equal, intervals have been colored. This method of spotting yarn is extremely rapid, as an entire cop of yarn may be spotted in a few moments.

While the invention thus provides a 95 method for producing ordinary spotted yarns much more economically and rapidly than has been possible heretofore, it may also be used to produce a new article of manufacture. Thus, by the method described, predetermined portions of the cop 100 of yarn may be impregnated with different colors which may be so arranged that when the yarn is unwound, it will be found to be dyed throughout its length in different colors arranged in accordance with the predetermined scheme or design. When this yarn is woven or knitted into a fabric, it produces a multicolor mixture such as 105 has heretofore been produced only by knit- 110

ting or weaving together a number of different threads of yarn which have been separately dyed in different colors.

The invention may be applied directly to 5 the dyeing of textile fabrics. In this case a mass of the fabric is piled up, either by folding a long strip or "piece" of the fabric in layers against the flat surface, or by winding it about a cylinder, which should 10 preferably be of a diameter considerably greater than the depth of the mass of fabric.

The dye is then forced into designated parts of the mass or pile of fabric, so that 15 all the layers of the pile are dyed by the same operation and in accordance with the same design. When the piece of fabric is spread out or unrolled, it will be found that it has been dyed throughout its entire length in accordance with the predetermined de- 20 sign.

While the invention may thus be used for a variety of different purposes, it is believed that its nature may be made plain by a detailed description of a single illustrative method embodying it. I will therefore, describe in detail a method of spotting yarn in accordance with the invention. In describing this method I shall refer to the accompanying drawing, in which—

30 Fig. 1 is a side view, partly in axial section, of a cop of yarn impregnated with dye in accordance with the invention;

Fig. 2 is a transverse section of the cop taken on the line 2—2 of Fig. 1;

35 Fig. 3 is an enlarged fragmentary side view of the cop, showing, in transverse section, the needle which is inserted in the mass when the dye is to be introduced, and indicating by a dotted line the area to be im- 40 pregnated by the dye;

Fig. 4 is a partial transverse section of the cop, showing, in longitudinal section, an apparatus by which the dye may be injected into the cop;

45 Fig. 5 is an enlarged perspective view of the needle of this apparatus;

Fig. 6 is a transverse section on the line 6—6 of Fig. 5; and

50 Fig. 7 shows a yarn spotted in accordance with the invention.

The first step in spotting yarn in accordance with my invention is to form the yarn into a mass in the regular manner. This may conveniently be done by winding a yarn 55 10 on a bobbin 11 so as to form the yarn into a cop such as is shown in Fig. 1.

Limited quantities of a liquid dye are then injected into the cop at predetermined points of its outer or inner surface.

60 Any apparatus or mechanism capable of projecting a limited quantity of liquid under pressure may be used to inject this dye into the cop. In order to insure a complete penetration of the cop by the dye, it is de- 65 sirable that the dye be injected through a

narrow opening or slit which may be formed in the cop by means of any sharp instrument such as a pin.

A simple apparatus for opening a slit in the cop and injecting the dye from the outer 70 surface of the cop is illustrated in Figs. 4, 5 and 6. This apparatus forms the subject matter of my divisional application Serial No. 634,648, filed April 26, 1923. The apparatus is a sort of squirt gun having a cylinder 15 in which the dye is placed. In this cylinder is a plunger 16 having a central opening. A rigid tube or stem 17 projects from the plunger and passes through a central hole in the cover 18 of the cylinder. A 80 nozzle 19 is screwed on the outer end of the stem 17. The nozzle 19 has a flat outer end 20 and contains a central hole 21. A sharp needle 25 projects outwardly from the nozzle. An open longitudinal groove 26 ex- 85 tends throughout the length of the needle 25. The needle extends through the hole 21 of the nozzle and its inner end is secured to a disc 27 containing a central hole 28. The disc 27 is clamped between the nozzle and 90 the end of the stem.

If desired, the needle 25 may be provided with a plurality of longitudinal grooves similar to the groove 26. As, however, I have found it desirable to make the needle 95 of as small cross-section as possible, I prefer to use a single groove as shown.

The distance which the needle 25 projects beyond the front surface 20 of the nozzle should not be greater than the depth 100 of the cop at the point at which the dye is to be injected, and may be much less than this depth. The shape of the portion of the cop colored may be varied by varying the proportion between the length of the 105 projecting part of the needle and the depth of the cop at the point at which the dye is injected. When it is desired to color a portion of the cop having a uniform cross-sectional area throughout its depth, I find 110 it desirable to use a needle which extends beyond the nozzle a distance only slightly less than the depth of the cop at the point at which the dye is to be injected. The nozzle and needle shown in the drawings are 115 proportioned to color a portion of uniform cross-sectional area at the central part of the cop. In order to color similar portions near the ends of the cop where its depth is less, a needle projecting a shorter distance 120 from the nozzle is used.

In injecting dye by means of the apparatus described, the needle 25 is first inserted squarely into the cop from a point 30 at the outer surface of the cop. This results 125 in opening a narrow slit 31 into the cop, as best seen in Fig. 3. This slit 31 extends inwardly nearly to the inner surface of the cop.

The outer end surface 20 of the nozzle 130

19 is then pressed firmly against the outer surface of the cop. This compresses the portion of the cop which surrounds the slit 31, to some extent, and also prevents any 5 dye from leaking between the end of the nozzle and the cop and thus spreading over the outer surface of the cop.

After the needle has been inserted and the nozzle has been pressed against the cop, 10 the stem 17 is held firmly in one hand while the cylinder 15 is moved slightly toward the nozzle, thus forcing through the nozzle a portion of the liquid dye contained in the cylinder. The movement given to the cylinder is a quick short jerk so that only a 15 small quantity of dye is forced through the nozzle, and this dye is forced out under considerable pressure. The amount of dye which is thus forced through the nozzle 20 determines the size of the spot formed on the cop, and with a little practice the squirt gun may be manipulated so as to inject just sufficient dye to form a spot of the size desired.

25 The liquid which is thus forced through the nozzle 19 follows the groove 26 and penetrates at once to the inner surface of the cop, that is to say, the surface which is against the bobbin 11. Furthermore, it has 30 been found that dye may, in this manner, be distributed uniformly along a line extending from the point 30 to the inner surface of the cop before any material part of it is drawn into the pores of the yarn by 35 capillary attraction. This dye then permeates evenly into the yarn about this line throughout the depth of the cop. The extent to which the dye spreads is shown by the area 32 within the dotted line in Fig. 40 3 and by the darkened areas 32 shown in Fig. 1. The portion of the cop which is dyed by the injection has substantially the same area at the inner surface of the cop as at the outer surface of the cop and its 45 cross-sectional area between these points is substantially uniform. Thus, as seen in the sectioned portion of Fig. 1, the sides 33 of a spot 32 are substantially straight, and as seen in Fig. 2, the ends 34 of the spot are 50 substantially straight, throughout the depth of the cop. It follows, therefore, that the injection has colored each layer of the yarn in the cop over the same area.

The superficial, as well as the cross-sectional, area of the portion of the cop which is dyed by the injection is elongated in shape as shown in the drawings. This I believe is caused, both by the shape of the slit 31 and by the fact that the dye permeates longitudinally of the strands of yarn more rapidly than across these strands.

55 Dye is injected into the cop at a number of different points. The injections may be made successively or simultaneously. The 60 points 30 at which the dye is injected may

be arranged in any desired manner on the surface of the cop. In order to secure a regular spotting of the yarn, however, these points should be located at substantially uniform distances along a spiral line extending over either the outer or the inner surface of the cop from one end of the cop to the other. Such an arrangement of the points 30 on the outer surface is illustrated 70 in Figs. 1 and 2. When the dye has been injected at points arranged in this manner, it will be found, when the yarn 10 is unwound, that the yarn has been colored at regular intervals throughout its length, as 75 seen in Fig. 7. The intervals between the colored portions or spots are, however, not of exactly equal length throughout the length of the yarn, owing to the fact that when the yarn is wound on the bobbin the turns nearest the bobbin are shorter than 80 the outer turns. This spacing of the spots has, however, proved to be an advantage, as it gives the desired mixed effect when the yarn is woven or knitted into a fabric. 85

If the dye injected at each of the points 90 30 of the cop has the same color, the spotted yarn will be similar to that which has been spotted by known methods. It is apparent, however, that in carrying out the method, dyes of different colors may be injected at 95 different points of the cop. If this is done, the yarn, when unwound, will be found to be dyed throughout its length with a number of different colors arranged in a regular manner corresponding to the arrangement 100 of the points on the cop at which the different colored dyes were injected. When such a thread is woven or knitted into cloth, it produces a multicolor mixture such as has heretofore been produced by weaving or 105 knitting together a number of separately dyed threads.

The application of the invention to the other uses will, it is believed, be understood 110 from the above description of the use of the invention in spotting yarn. Thus in applying the invention to the partial dyeing of knitted or woven fabric, the same procedure is followed, and the same, or a similar, apparatus may be used to inject the dye into the 115 mass. It may be noted, however, that when this apparatus is used for injecting dye into a mass of fabric, or into a mass of yarn wound in such a manner that the turns of the thread of one layer are not substantially parallel to the turns of the next layer, the narrow opening made by the needle is approximately circular in cross-section instead of being a long slit, such as is formed by thrusting the needle into a cop. Furthermore, in the case of a pile of fabric, or a cross-wound mass of yarn, the cross-section 120 of the portion colored by each injection is not elongated like the colored portion of the 125 cop. 130

What is claimed is:

1. A method of dyeing textiles, comprising forming the textile to be dyed into a mass in a regular manner, and injecting a limited quantity of liquid dye into the mass under pressure so that the dye penetrates the mass along the line on which it is injected before any substantial portion of it is absorbed into the pores of the textile.
- 10 2. A method of dyeing textiles, comprising forming the textile to be dyed into a mass in a regular manner, and injecting a limited quantity of liquid dye into the mass under pressure, so that the liquid is distributed uniformly along a line extending into the mass before any material portion of it is absorbed into the pores of the textile.
- 20 3. A method of dyeing textiles, comprising forming the textile to be dyed into a mass in a regular manner, and injecting a limited quantity of liquid dye into the mass from a point at one surface thereof and under such pressure that the dye penetrates to the opposite surface of the mass before any substantial portion of it is absorbed into the pores of the textile, so that the dye permeates into the portion of the mass surrounding the line on which the dye is injected throughout the depth of the mass.
- 30 4. A method of dyeing textiles, comprising forming the textile to be dyed into a mass in a regular manner, forming a narrow opening into the mass, and injecting a limited quantity of liquid dye into the mass through said opening.
- 35 5. A method of dyeing textiles, comprising forming the textile to be dyed into a mass in a regular manner, forming a narrow opening into the mass, and injecting a limited quantity of liquid dye into the mass through said opening under such pressure that the dye penetrates to the bottom of the opening before any substantial portion of it is absorbed into the pores of the textile, so that the dye spreads into the portion of the mass adjacent to the sides of the opening.
- 45 6. A method of dyeing textiles, comprising compressing a mass of the textile to be dyed, and injecting a limited quantity of liquid dye into the compressed mass under pressure.
- 50 7. A method of spotting yarn, comprising forming the yarn into a mass by winding it, and injecting, under pressure, a limited quantity of liquid dye into the mass.
- 55 8. A method of spotting yarn, comprising injecting, under pressure, a limited quantity of liquid dye into a wound mass of the yarn.
- 60 9. A method of spotting yarn, comprising applying external pressure to a portion of the surface of a mass of the yarn, and injecting, under pressure, a limited quantity of liquid dye into the mass from a point on the surface to which such external pressure is applied.
- 65 10. A method of spotting yarn, comprising pressing a nozzle firmly against the surface of a mass of the yarn, and injecting a limited quantity of liquid dye into the mass through the nozzle.
- 70 11. A method of spotting yarn, comprising forming a narrow opening into a mass of the yarn, and injecting, under pressure, a limited quantity of liquid dye into said opening.
- 75 12. A method of spotting yarn, comprising forming a narrow opening into a mass of the yarn, pressing a nozzle firmly against the surface of the mass at the outer end of the opening, and injecting a limited quantity of liquid dye into the mass through said nozzle and said opening.
- 80 13. A method of spotting yarn, comprising forming the yarn into a mass by winding it, and injecting limited quantities of liquid dye into the mass at regularly spaced points of its surface.
- 85 14. A method of spotting yarn, comprising injecting limited quantities of liquid dye into a wound mass of the yarn at points equally spaced along a spiral line on a surface of the wound mass.
- 90 15. A method of spotting yarn, comprising injecting limited quantities of different colored dyes into different portions of a mass of the yarn.

In testimony whereof I have hereunto set my hand.

HENRY E. VAN NESS.
